UNITED STATES PATENT OFFICE.

ALBERT W. METZNER AND JOHN Q. SHERMAN, OF DAYTON, OHIO; SAID METZNER
ASSIGNOR TO SAID SHERMAN.

ROTARY PUNCH AND DIE MECHANISM.

Application filed June 1, 1920. Serial No. 385,545.

To all whom it may concern:

Be it known that we, ALBERT W. METZNER and JOHN Q. SHERMAN, citizens of the United States, and residents of the city of Dayton, in the county of Montgomery and State of Ohio, have invented a certain new and useful Rotary Punch and Die Mechanism, of which the following is a full, clear, and exact description, reference being had to the drawings forming part of this specification.

Our invention relates to punch and die mechanisms and has special relation to the punching of a series of holes in webs of paper.

There has been great difficulty in the prior art in rapidly and accurately punching paper webs or strips, due in part to the failure to provide a properly operating rotary punch. As soon as any high rate of speed has been attempted in the past, our information and experience is that imperfect work has resulted with failure of the punches and dies to make clean holes, and adherence of the "confetti" or punchings either to the paper or the dies.

It is the object of our invention to provide a mechanism of rotary mode of operation which positively clears the paper and itself as well of all punchings of confetti and operates at a high rate of speed, without any tendency to fail in accurate and clean work.

Among other things, we employ a plunger operating under spring tension or otherwise, in the die units themselves, with or without other clearing devices or structures, same serving as a guide to insure accurate registry of punch and die, and chiefly designed to cooperate with the punch in grasping the paper firmly, thereby carrying the portion of the paper to be removed bodily into the die and subsequently ejecting it. We also provide for a piercing pin which is preferably cam and spring controlled to positively pierce the "confetti" resulting from the punching operation, thereby positively preventing its adherence to the paper strips.

We accomplish our objects and advantages by that certain construction and arrangement of parts to be hereinafter more specifically pointed out and claimed.

In the drawings,

Figure 1 is a side elevation, more or less

diagrammatic, showing the driving connections and interconnections for insuring perfect accuracy of feed;

Figure 2 is a side elevation of one of the die units showing its method of mounting on the driving shaft therefor, for quick adjustability;

Figure 3 is a detail section taken through the device shown in Figure 2;

Figure 4 is a detail end elevation of one of the punch pins, showing the cut-away nature thereof;

Figure 5 is an end elevation showing a pair of punch and die drums, with their shafts, and the connection between them, whereby both are driven at exactly the same speed without chance of dead centering;

Figure 6 is a detail section taken through a punch and die unit, at the point of punching, showing likewise the brush device for removing adherent confetti from the paper;

Figure 7 is a detail elevation, partly in section, adjacent the punch and die, showing the operated piercing pin feature of our invention;

Figure 8 is a detail plan view showing the punch carrier in section and illustrating a method of mounting the punch pin operating bars;

Figure 9 is a detail, sectional view, partly in elevation, showing a modification of the piercing pin feature; and

Figure 10 is a detail elevation of the piercing pin shown in Figure 7.

No attempt has been made to show a complete machine with all driving connections, since our punch is designed for use with any desired means of power, either as a separate mechanism or as a part of a machine for printing, and numbering webs of paper. As a particular use for our machine, we refer to the use thereof in preparing marginally perforated paper for manifolding machines or autographic registers.

In such machines it is customary to print the various duplicate strips in multiple and to punch the desired number of double series of holes intermediate the edges of the full width webs, later dividing the webs lengthwise between the rows of perforations, and of the double series.

Our machine is readily adapted for such work, and in the drawings the punch and die units are shown to have a double set of elements, although this will be understood

to be merely for purposes of illustration. The first six views in the drawing show the form of mechanism wherein the piercing pin is unitary with the punch which is described first because of its simplicity.

The frame 1 of the machine provides suitable journals for a shaft 2 for punching units, and a shaft 3 for the die units.

The shaft 3 has keyed thereon an eccentric 10 stud 4 and crank 4^a, said crank and stud being set apart at an angle. The shaft 2 has like cranks 4^b at each end, lying parallel with the cranks adjacent to them on the shaft 3. Links 5, 5, connect the cranks at 15 each side of the machine to slide blocks 6 which are suitably mounted in guideways 7. From this construction, the driving of the shaft 3 will positively drive the shaft 2 in perfect alignment, all dead centering being 20 prevented by the angling relation of the cranks with relation to each other, always, of course, keeping the cranks of each pair in parallel.

Forward of the machine, from the punch 25 and die shafts, we have shown the printing rollers 8, 8, having gears 8^a, which are driven by a gear 9, which also drives a gear 10 on the die shaft 3. The paper is stored on a roll 11, from which it passes to the printing 30 rollers, and thence over idlers 12 which steady and support the paper and provide a tangential path therefor, between the punch and die units.

The punch and die units are, as has been 35 noted, rotary, and in addition there is no attempt at retaining the matching parts in parallelism, since due to the nature of the punch and die elements they may be mounted radially and come into parallelism only 40 at the instant of full penetration of the punch into the die.

As shown in Figures 2 and 3, the drums, which form the rotary members of the die and punch units, are preferably made up in 45 two portions 13 and 14, one of which is provided with a key-way 15 for keying to the operating shaft.

Sleeve portions 16 are formed on the halves of the drums which are flanged and 50 suitably bolted together at 17^a, so as to be readily loosened and adjusted along the shafts on which they are mounted, and, in addition, so as to be readily removable and replaceable from and on said shafts.

The punch units 17 are set radially into 55 the periphery of the drums 18 and in the desired spaced relation, said spacing to correspond with that of the dies in the die drums 19. The punches have a hollow interior 20 and are also cut across the ends at right angles, so as to form four notches 21 in their ends (Figure 4).

While this special form of punch has been 60 found quite satisfactory in use by us, we do not at all limit the range of design of the

punches to that specific shape now described. We have in fact obtained excellent results by the use of punches having plain or slightly concaved ends.

The dies are of special construction, and 70 in the embodiments selected for illustration of the invention are in part made up to co-operate with the special form of punch. Cylindrical pieces 22 form the dies proper, and are set into suitable orifices in the periphery of the drums 19.

Mounted to slide in the cylindrical die pieces are the plungers 23, which are flanged at the inner end and actuated by coiled springs 24, bearing against said flanged 80 ends, and held in place by screws 25 set into the die holes of the drums.

As shown the apices of the plungers or pins may be formed with ribs to fit into the notches in the punches and will be held so 85 as to lie flush with or slightly beyond the outer edge of the dies when in normal position. The ends of the plungers will ordinarily be made conical in shape to fit the depressions in the punches and in the simplest 90 form of our invention has points 26 formed at the apices of the punches, although ordinarily they will be independently operable.

It will be noted that the drums as arranged on the shafts, are spaced apart at the 95 point of contact of the punches with the dies and that the paper is passed between the drums in a plane tangential to the drums, but not in contact with either. For some materials it might not be absolutely necessary for the material to pass freely between the two drums, but for paper, we have found this very necessary to avoid any 100 chances of the drums themselves interfering with the motion of the paper.

As a punch and die approach each other, the punch and plunger engage the paper on 105 two sides and while maintaining this grasp the punch and plunger enter the die thereby punching out the desired shaped hole. In 110 entering the die the punch depresses the plunger within the die, leaving its spring to force it outwardly through the die as the punch leaves. The punching left in the die is thus ejected by an element acting through 115 the die itself, in an opposite direction to the punch.

The plungers in the dies due to their tapered ends and the similarly shaped sockets in the punches will act to align the 120 punches and dies and as noted, to eject the confetti. However, the main reason for using this plunger is to grip the portion of paper, or other material to be punched out, firmly against the punch when the punch 125 comes in contact with the plunger, thus holding the portion to be punched out in an absolute parallel position and carrying it into the die regardless of whether it is punched absolutely clean all the way round, 130

and by the portion to be punched being carried into the die in this fashion it will be torn away from the paper web or other material at the point where it may not be punched clean. Without the use of this plunger the slight shearing of the punch on one side would cause the paper or other material to be only partially punched from the main piece, and by it adhering to one portion it would curl down into the die. By being carried squarely into the die, by gripping between plunger and punch it will positively be torn out, regardless of any possible partial shearing of the punch leaving an open space or non-cutting space between the punch and the die.

As shown in Figure 7, the method of mounting the punches is slightly different from the form illustrated in the simpler form of the device, the punches being tightly fitted into bushings 31 driven into the mounting drums and screws 32 employed to hold the punches in place. This form of mounting permits of the changing of the punches without marring the drum or mounting device.

In the dies for the more elaborate form of structure the means for mounting the plunger and the plunger itself are the same as that shown in the first six figures and are similarly numbered, except for the fact that the plunger has an axial hole 33 therein and does not have the pin point at its apex, the pin point being provided by a separate mechanism actuated by cams.

In the preferred embodiment showing the independent pin point elements, there is mounted on the two faces of the lower drums or die carrying drums an annular plate 34. The small screws 35, which hold the plunger springs in place are perforated with an axial hole similarly to the plungers, and pins 36 are provided which extend up through the plungers, said pins having a small groove 36a around their tips.

These pins are formed with shoulders 37 and thickened ends 38, there being springs 39a mounted over the pins and acting between the shoulders and the screws 35. The thickened ends extend through and are guided in the annular plates 34.

There is one plain shaft or bar 39, and one eccentric shaft or bar 40, mounted alongside of the die unit shaft which carry cross bars 41. These cross bars are provided with journals 42 at one end to engage over the shaft 39, and are preferably forked as at 43 at the other end to engage the eccentric shaft 40. The bars straddle the die units closely adjacent the sides thereof, and are arched up as at 44 to clear the mounting sleeves. Mounted on the arched portions of the bars are cam plates 45 which lie in the path of the thickened ends of the pins. As may be observed the revolving of the eccentric

shaped bar or shaft 40 will alter the position of the cam plate with relation to the path of the pins for any desired adjustment.

As shown in the drawings, there is one of these straddling bars and cam devices for each side of each one of the die units and when each die approaches the position of engagement with a punch, the pins will be thrust upward through the plungers and will impale the paper engaged between the punch and die, and hold it as the punch and die are disengaged from each other after which the pin will be drawn by its spring to a position with its point inside of its respective plunger. Other arrangements of dies, punches, straddling bars and cams may readily be devised in addition to the above.

Due to the conformation of the ends of the pins they will puncture and grasp the confetti punched out of the paper, and their withdrawal will strip said confetti away at the apex of the plungers in each instance.

A different form of impaling or piercing pin device is shown in Figure 9 wherein the pin 50 has its shoulder 51 located in the space between the screw that retains the plunger in place and the die itself. The spring 52 on the pins bears between the base of the plunger and the shoulder on the pin, and the usual spring for the plunger is not interfered with by this construction. The protruding end 53 of the pin contacts with a cam plate 54, which may be mounted on a straddle bar, as in the first instance described.

In order to clear the paper of any punchings that may adhere thereto, in spite of all of the above described agencies, we have devised a brushing mechanism, which acts twice on each hole punched.

Thus the paper is drawn over idler rolls 27, 28 and 29 being bent to the left in passing under the roll 27 and to the right in passing under the roll 29. The brush 30, operated by means of a twisted belt, from the shaft 3, and thus revolving in the opposite direction to the movement of the paper, acts on the paper as it is bent in passing the two rollers above noted, so that any projecting edge of a punching, will be caught by the brush and swept out of lodgment, in the paper.

We believe the principles of construction and operation of our invention are made clear by the above concrete examples of its use and wish our claims that follow to be construed with the full application of the doctrine of equivalents.

Having thus described our invention, what we claim as new and desire to secure by Letters Patent, is:—

1. A punching mechanism for the purpose described and having rotary members, comprising in part punch elements and die elements, the same being adapted to contact

with each other to effectuate a punching operation, and means in the die element engaging the punched out material and then ejecting it from the die elements, by a force exerted therethrough in the opposite direction to that of the punch elements, said means adapted to be moved out of their way by the punches.

2. A punching mechanism for the purpose described and comprising rotary members, a punch carried by one rotary member, a die carried by another rotary member, said punch being adapted to enter the die during the rotation of the rotary members, and a member acting through the die in an opposite direction to the punch and adapted to engage the paper to be punched together with said punch, and to retain and eject said paper, said member adapted to be moved out of the way by the punch while retaining the punched out material between said member and the punch.

3. A punching mechanism for the purpose described and comprising rotary members, a punch carried by one rotary member and a die carried by another rotary member, said punch and die being adapted to come into operative relation during the rotation of said members, and a plunger slidable in the die, said plunger being adapted to enter the punch to cooperate with the punch to guide it into the die.

4. A punching mechanism for the purpose described and comprising rotary members, a punch carried by the one rotary member, and a die carried by the other rotary member, said punch and die being adapted to come into operative relation during the rotation of said members, and a plunger slid- able in the die and capable of extension beyond the mouth thereof, said plunger and punch having matching ends, whereby the plunger engages in the punch and guides the punch into the die.

45 5. The combination of a punch, a die, rotary means for carrying said punch and die through radial paths toward and away from operative relation with each other so as to operate on a moving web of material, and means operating within the die for engagement with the punch during its punching operation to impale the material punched.

6. The combination of a punch, a die, rotary means for carrying said punch and die through radial paths toward and away from operative relation with each other so as to operate on a moving web of material, and means operating within the die for guiding the punch into engagement therewith, said means comprising a plunger adapted to contact with the punch and move together with the punch into the die, said punch and plunger having matching ends, and said plunger adapted to engage in the material punched.

65 7. The combination of a punch, a die, ro-

tary means for carrying said punch and die through radial paths toward and away from operative relation with each other so as to operate on a moving web of material, and means operating within the die for guiding the punch into engagement therewith comprising a spring-pressed plunger within the die, said plunger lying with its end normally beyond the die opening, and matching ends for the punch and plunger. 75

8. The combination of a punch, a die, rotary means for carrying said punch and die through radial paths so as to act upon a moving web of material, and a spring-plunger within the die adapted to force out of the die the material left therein by the punch, said plunger having a point thereon adapted to impale the punched out material, said plunger movable inwardly of the die together with the punch. 80 85

9. The combination of a radially moving punch and a radially moving die, said punch and die adapted to come together for action on a moving web of material, a plunger in the die, said plunger having a conical end, and a conical recess in the punch adapted to match with said conical end on the plunger, and means for projecting the plunger into contact with the punch prior to its entrance into the die. 90 95

10. The combination of a radially moving punch and a radially moving die, said punch and die adapted to come together for action on a moving web of material, a plunger in the die, said plunger having a conical end, and a conical recess in the punch adapted to match with said conical end on the plunger, and means for projecting the plunger into contact with the punch prior to its entrance into the die, said punch having a notched periphery around said conical recess. 100 105

11. The combination of a radially moving punch and a radially moving die, said punch and die adapted to come together for action on a moving web of material, a plunger in the die, said plunger having a conical end, and a conical recess in the punch adapted to match with said conical end on the plunger, and means for projecting the plunger into contact with the punch prior to its entrance into the die, said plunger having an impaling point at its apex, and a central recess in the conical end of the punch adapted to receive said impaling point. 110 115

12. In a punching machine, the combination of a pair of rotary shafts, drums or the like on said shafts, positioned so that their peripheries do not contact with each other, means for constantly moving a web of paper between said drums, said means acting on the paper on both sides of the drums, tangentially thereto and out of contact therewith, dies radially affixed in one drum, and 120 125

5 punches radially affixed in the other, said punches being adapted to enter the dies thereby punching said paper, whereby the feed of the paper is independent of the punch carriers.

10 13. In a punching machine, the combination of a pair of rotary shafts, drums or the like on said shafts, positioned so that their peripheries do not contact with each other, means for constantly moving a web of paper between said drums, tangentially thereto and out of contact therewith, said means acting on the paper on both sides of the drums, dies radially affixed in one drum, and punches 15 radially affixed in the other, said punches being adapted to enter the dies thereby punching said paper, and means on the drum carrying the dies to guide the punches on the other drum into the said dies.

20 14. In a punching machine, the combination of a pair of rotary shafts, drums or the like on said shafts, positioned so that their peripheries do not contact with each other, means for constantly moving a web of paper 25 between said drums, tangentially thereto and out of contact therewith, said means acting on the paper on both sides of the drums, dies radially affixed in one drum, and punches radially affixed in the other, said 30 punches being adapted to enter the dies thereby punching said paper, and means on the drum carrying the dies to guide the punches on the other drum into the said dies, comprising spring plungers mounted in said 35 dies and adapted normally to project therefrom.

40 15. In a punching machine, the combination with a moving punch and die, of means for moving a web of paper intermediate said punch and die, and clearing means for removing confetti from the punched portions of said paper, comprising in part a rotary brush, and means for causing said paper to traverse an angular path adjacent 45 said brush, for the purpose described.

50 16. In a punching machine, the combination with a moving punch and die, of means for moving a web of paper intermediate said punch and die, and clearing means for removing confetti from the punched portions of said paper, comprising in part a rotary brush, and a series of rollers located adjacent the brush and causing the paper to traverse a plurality of angular paths 55 opposed to each other for action by the brush.

60 17. In a punching machine, the combination of a pair of rotary shafts, drums or the like on said shafts, positioned so that their peripheries do not contact with each other, means for constantly feeding a web of paper tangentially between said drums but out of contact therewith, said means acting on the paper on both sides of the drums, means for driving one of said shafts, positive driving 65 connection between the two shafts, and dies

in one drum and punches in the other adapted to act on the web of paper.

18. In a punching machine, the combination of a pair of rotary shafts, drums or the like on said shafts, positioned so that their peripheries do not contact with each other, means for constantly feeding a web of paper tangentially between said drums but out of contact therewith, means for driving one of said shafts, positive driving connection between the two shafts, and dies in one drum and punches in the other adapted to act on the web of paper, said positive driving connection comprising a double set of links, each set interconnected by a sliding element.

19. In a paper punching device, the combination with dies and punches adapted to come together, of opposed rotary elements for carrying the punches and dies, means for driving both of the opposed rotary elements, and paper feeding means adapted to feed paper between the opposed rotary elements at a speed uniform with the linear movement of the dies and punches, said means acting on the paper on both sides of the drums, said rotary elements being spaced apart so as to be out of contact with the paper.

20. In a paper punching machine, a punch and a die, means for moving the punch into the die, and means movable through the die together with the punch and adapted to engage and impale the portion of the paper that is to be punched during its movement into the die.

21. In a machine for punching paper, the combination with a punch and a die, the same being relatively movable, of a plunger element moving through the die and adapted to engage paper between it and the punch, and a confetti impaling member moving through the plunger and adapted to be stripped by the plunger for the purpose described.

22. In a machine for punching paper, the combination with a punch and a die, the same being relatively movable, of a plunger element moving through the die and adapted to engage paper between it and the punch and an impaling pin mounted to move axially through the plunger, and means for moving the point of said pin out through the end of the plunger at the time of relative punch and die movement, and without drawing said point within the plunger at the close of the punching movement.

23. In combination, a shaft, a revolving die-carrying element carried by said shaft, a series of dies set into said revolving element, spring-controlled pins mounted to extend through the dies for impaling confetti, and arm straddling the shaft, cam means for the arm adapted to contact with the pins at a selected point during said re-

volving movement, said spring control for the pins adapted to retain them in position for said cam contact.

24. In combination, a shaft, a revolving die-carrying element carried by said shaft, a series of dies set into said revolving element, spring-controlled pins mounted to extend through the dies for impaling confetti, an arm straddling the shaft, cam means for the arm adapted to contact with the pins at a selected point during said revolving movement, said spring control for the pins adapted to retain them in position for said cam contact, rods or the like for carrying said straddling arm, one of said rods, at least, having eccentric means for engaging the said arm, whereby the operation of said eccentric means will adjust the position of the cam.
25. In a device of the character described, the combination of a pair of shafts, a drum on each shaft, said drums adapted to approach each other at one point but not to come into contact with each other, means for driving both of said shafts at a constant speed, means for feeding paper between said drums at a constant speed, said means acting on the paper on both sides of the drums, punches mounted on one drum, and dies set in the other, as and for the purpose described.
26. In a device of the character described, an annular element having a hole therein, a die set into the hole in said element, a plunger in the die and having means for preventing its movement outwardly through the die, means closing up the hole at the in-

ward end of the die, and a spring between said last-noted means and the plunger, for the purpose described, said plunger having 40 an end formed with a taper and ribs thereon, said above-noted parts being in combination with a punch adapted to move into the die, and having an end formed inversely to the end of the plunger. 45

27. In a device of the character described, the combination with an annular element, of a die set therein, a plunger set in said die and adapted to move therein, a pin extending through the plunger, means for retaining the plunger in place in the die, a spring adapted to force the plunger outwardly through the die, and a spring adapted to force the pin inwardly through the plunger. 50

28. In a device of the character described, the combination with an annular element, of a die set therein, a plunger set in said die and adapted to move therein, a pin extending through the plunger, means for retaining the plunger in place in the die, a spring adapted to force the plunger outwardly through the die, and a spring adapted to force the pin inwardly through the plunger, 60 said parts above being in combination with a punch adapted to move into the die and carry the plunger with it in said movement, and an element adapted to move the pin outwardly through the plunger during said punch movement and permitting its retraction through the plunger following said 65 movement. 70

JOHN Q. SHERMAN.
